UNITED STATES PATENT OFFICE.

OTTO HAJEK AND EMANUEL BLAUHORN, OF VIENNA, AUSTRIA.

LUBRICATING-OIL PUMP.

Application filed April 3, 1922. Serial No. 549,158.

To all whom it may concern:

Be it known that we, OTTO HAJEK and EMANUEL BLAUHORN, citizens of the Republic of Austria, residing at Vienna, Austria, have invented certain new and useful Improvements in Lubricating-Oil Pumps, of which the following is a specification.

This invention relates to valveless lubricating oil pumps having two cylinders arranged in one casing. One of the cylinders, (the pumping cylinder), contains the pumping piston, while the other cylinder (the distributing cylinder) contains the distributing piston, and the motion of the two pistons is such that the pumping piston makes twice as many strokes as the distributing piston so that two oil ducts can be supplied with oil alternately.

The motion of the two pistons is produced by means of two levers mounted rotatably on an axle. The distributing piston is actuated by one arm of one lever, the other arm of which is driven by an eccentric fixed to a shaft whereby the said piston receives its to-and-fro motion.

The motion of the pumping piston is produced by a second lever which is mounted on the same shaft and which is suitably connected by an arm to the pumping piston while the second arm is forked and is actuated by means of a double tappet, so that the piston receives a positive to-and-fro motion.

An embodiment of this invention is illustrated by way of example in the accompanying drawings in which:—

Figure 1 is a longitudinal section of the improved lubricating oil pump, and

Figure 2 is a cross-section thereof. Figures 3, 4, 5, 6 and 7 illustrate the double tappet and show diagrammatically the rocking lever actuated by said double tappet in five positions which are assumed by the double tappet and the lever during one complete revolution of the tappet shaft.

1 is the oil vessel; this oil vessel contains the casing of the lubricating pump 2. In this casing are the distributing piston cylinder 3, the pumping piston cylinder 4, the duct 5 for the admission of the oil, and the ducts 6 and 7 for the exit of the oil. 8 is the pumping piston; 9 is the distributing piston; 10 is the connection between the pumping piston cylinder and the distributing piston cylinder through which the oil passes from the oil vessel into the pumping

piston cylinder during the suction stroke of the pumping piston 8 whereas, on the delivery stroke of the pumping piston 8 the said oil is forced from the same connection 10 alternately into the duct 6 and the duct 7.

In the oil vessel there is located a shaft 11 and on this shaft there is mounted rotatably a lever 12 which is suitably connected to the distributing piston by means of one arm 12^a and is provided with a second and suitably recessed arm 12^b in which the eccentric 13 is located. The eccentric 13 is fixed to a shaft 14.

The pumping piston 8 is connected to an arm 15^a of the lever 15; the other arm of this lever is forked and at the ends of the fork are mounted two anti-friction rollers 16, 17. On the shaft 14 and fixed to it is also a double tappet 18. This double tappet has relatively to the two rollers 16, 17, a position such that when it rotates it is in contact with only one roller, and comes into contact with the other roller only when it has come out of contact with the other roller.

The said rollers are provided for the purpose of diminishing friction but they are not indispensable for the operation of the apparatus and in their stead the two parts of the lever 15 facing the tappet may be arranged to be conducted or actuated by the said tappet. On following the rotational motion of the double tappet in Figures 3, 4, 5, 6, and 7, it will be seen that the lever 15, and consequently also the pumping piston 8 are positively actuated in the direction of the movement of the delivery stroke of the pumping piston, as well as in the direction of the suction stroke of this piston.

In Figures 3 to 7, the lever arm 15^a for connecting the pumping piston, as shown diagrammatically has a simple line.

Figure 3 shows the position of the double tappet 18 where the arm 15^a of the lever has reached its lowest point, and contact of the rising face of the tappet with the roller 17 is just ceasing. In this position the double tappet is not yet in contact with the roller 16.

Figure 4 shows the position of a double tappet in which it has already quitted the roller 17 of the lever and has come into contact with the roller 16. At this stage it begins to actuate the roller 16 for the purpose of raising the arm 15^a.

Figure 5 shows the double tappet and the

lever in a position in which the arm 15^a has already completed a part of the upward movement, which upward movement attains the highest degree when the double tappet 5 begins to move out of contact with the roller 16 as is shown in Figure 6 for the purpose of coming again into contact with a roller 17 in continued rotation.

Figure 2 shows the lubricating apparatus 10 comprising a plurality of lubricating pumps. In this construction two eccentrics 13 are provided and also two arms 12^a which are connected together by a bar 19 so that engagement with the distributing piston is 15 effected by means of the bar 19.

What we claim is—

1. In a lubricating pump, a pumping cylinder, a pumping piston arranged in said cylinder, a rocking lever having a first arm 20 for actuating said pumping piston and a second forked arm, a shaft, and a double tappet fixed on said shaft and located in such position relatively to said forked arm as to contact with the two ends of the fork of the 25 lever in succession and thereby move one end of said fork in one direction and the other end of said fork in the other direction, each half of the double tappet being capable of alone reciprocating the piston positively 30 once, so that two reciprocations of the piston occur at each complete revolution of the double tappet.

2. A lubricating pump as claimed in claim 1 in which the ends of the forked arm and 35 tappet are so arranged that each tappet contacts with one end portion of said arm only after the other tappet has released contact with the other end portion of said arm.

3. In a lubricating pump, a pumping cylinder, a pumping piston arranged therein, 40 a rocking lever having an arm engaging

said piston, a forked arm part of said lever, a rotatable shaft, and a substantially elliptical cam arranged on said shaft and forming 45 a double tappet designed to successively engage the tines of the forked arm for causing positive movement of the piston in opposite directions, each half of the double tappet being capable of alone reciprocating the piston 50 positively once, so that two reciprocations of the piston occur at each complete revolution of the double tappet.

4. A lubricating pump including a casing, a pumping cylinder and a distributing cylinder arranged in said casing, a port placing the interiors of said cylinders in communication, an inlet port and a plurality of outlet ports communicating with the interior of the distributing cylinder, means adapted to connect the first mentioned port to the inlet port, a distributing piston arranged within the distributing cylinder, a pumping piston arranged in the pumping cylinder, a shaft, a rocking lever arranged 60 on said shaft and engaging said distributing piston, a second lever mounted on said shaft and engaging the pumping piston, a forked arm forming part of the second lever, a second shaft, a double tappet mounted on the second shaft and arranged to successively 65 engage the tines of the forked arm, and means arranged on the second shaft for rocking the first lever, each half of the double tappet being capable of alone reciprocating 70 the piston positively once, so that two reciprocations of the piston occur at each complete revolution of the double tappet.

In testimony whereof they affix their signatures.

EMANUEL BLAUFORN.
OTTO HAJEK.
